(57) **CLAIM**

The ornamental design for a cladding element for building, as shown and described.

DESCRIPTION

1. Cladding element for building
2. Cladding element for building
3. Cladding element for building
4. Cladding element for building
- 1.1 : Perspective
- 1.2 : Perspective
- 1.3 : Front
- 1.4 : Left
- 1.5 : Top
- 1.6 : Bottom
- 2.1 : Perspective
- 2.2 : Perspective
- 2.3 : Front
- 2.4 : Left
- 2.5 : Top
- 3.1 : Perspective
- 3.2 : Perspective
- 3.3 : Front
- 3.4 : Left
- 3.5 : Top
- 3.6 : Bottom
- 4.1 : Perspective
- 4.2 : Perspective
- 4.3 : Front
- 4.4 : Left
- 4.5 : Top

The front view of figure 1.3, 2.3, 3.3 and 4.3 is identical to the back view, therefore, the back views are omitted; the left view of figure 1.4, 2.4, 3.4 and 4.4 is identical to the right view, therefore, the right views are omitted; the top view of figure 2.5 and 4.5 is identical to the bottom view, therefore, the bottom views are omitted.
